ABSTRACT

A voltage regulator includes a first circuit to generate a difference signal based on an input reference voltage, a regulated output voltage, and a signal on a feedback node. The voltage regulator includes a second circuit to provide the regulated output voltage on the output node based on the difference signal. The second circuit includes a first transistor coupled to receive the difference signal, a first feedback circuit to provide a first feedback signal to the feedback node, and a second feedback circuit to provide a second feedback signal to the feedback node. An open loop frequency response of the voltage regulator has a first pole and a second pole and the first feedback signal may adjust the frequency of the second pole based on a load current. The second feedback signal may adjust loop gain based on the load current.

POLE FREQUENCY TRACKING IN LOAD COMPENSATED AMPLIFIERS

BACKGROUND

Field of the Invention

This application relates to integrated circuits and more particularly to generating a reference signal in integrated circuits.

Description of the Related Art

In general, a voltage regulator is a circuit designed to maintain a constant output voltage. A linear regulator typically regulates its output voltage by controlling a difference between the output voltage and an input voltage. Referring to FIG. 1, voltage regulator 100 is a low power, low dropout (LDO) regulator for high load current applications. In general, voltage regulator 100 compares regulated voltage VREG to reference voltage VREF and adjusts regulated voltage VREG accordingly. This operation occurs with stable operation, i.e., with a predetermined phase margin and maintains sufficient spacing between a dominant pole and a second pole to avoid oscillation. A feedback circuit is included to maintain stable operation over varying load conditions and across a wide range of load currents, e.g., a range spanning over three orders of magnitude of current.

P-channel metal oxide semiconductor field effect transistor (i.e., PMOS transistor) 128 is coupled between power supply node VDD and output node 130, which couples to a load circuit (i.e., a load) and provides a regulated voltage VREG to the load. This load circuit is represented as a combined resistance and capacitance (RL and CL, respectively). The load circuit dominant pole ω_{p1} for voltage regulator 100:

$$\omega_{p1} = \frac{1}{R_L C_L}.$$

By controlling the output current of transistor 128, regulated voltage VREG is regulated to a target level. PMOS transistor 128 has a source terminal coupled to power supply node VDD, a drain terminal coupled to output node 130, and a gate terminal commonly coupled with one or more gate terminals of at least one other PMOS transistor. The gate terminal of PMOS transistor 128 acts as a control terminal to control the current provided to the load by PMOS transistor 128.

The control signal provided to the gate terminal of PMOS transistor 128 is generated using two amplifier circuits. Amplifier circuit 150 is a transconductance amplifier including n-channel metal oxide semiconductor field effect transistor (i.e., NMOS transistor) 102 and NMOS transistor 104, which are coupled as a differential pair of transistors. Amplifier circuit 150 compares regulated voltage VREG and reference voltage VREF, which in an embodiment is generated by a reference voltage generator (not shown). The source terminals of NMOS transistor 102 and NMOS transistor 104 are coupled to a drain terminal of NMOS transistor 106, which is configured as a current source that uses bias voltage VBIAS to provide a bias current to the differential pair of transistors. PMOS transistors 112, 114, 116, and 118 form a cascoded current mirror where PMOS transistor 118 mirrors PMOS transistor 116 and PMOS

transistors 112 and 114 are cascode devices. PMOS transistor 112 and PMOS transistor 114 have the same size, which is selected to maintain PMOS transistors 116 and 118 in a saturation region of operation. The cascode structure converts the input voltages to currents and applies the result to a common gate stage. PMOS transistors 112, 114, 116, and 118 coupled to NMOS transistors 102 and 104 form a folded cascode stage modified to receive a feedback voltage on feedback node 136.

Drain terminals of NMOS transistor 102 and NMOS transistor 104 provide a differential signal to source terminals of PMOS transistor 112 and PMOS transistor 114, thereby causing a voltage on node 134 that corresponds to the difference between regulated voltage VREG and reference voltage VREF. PMOS transistors 116 and PMOS transistor 118 have commonly coupled gate terminals. PMOS transistor 116 and PMOS transistor 118 are asymmetrically coupled (e.g., do not have commonly coupled source terminals) which improves stability. The source terminal of PMOS transistor 118 is coupled to power supply node VDD and a drain terminal of PMOS transistor 118 is coupled to the drain terminal of NMOS transistor 102. However, the source terminal of PMOS transistor 116 is coupled to receive a feedback voltage on feedback node 136. Feedback node 136 couples to the source terminal of PMOS transistor 116 to provide a feedback voltage to dynamically control operation of error amplifier circuit 150, as well as dynamically controlling a location of the second pole based on the load current. Parasitic capacitance C1, which is coupled in parallel between the supply voltage node and the drain terminal of PMOS transistor 114, provides a second pole of regulator 100:

$$\omega_{p2} = \frac{g_{dsn} + g_{mpx}R_{fb}g_{mp}}{R_L C_1}.$$

The output of the amplifier circuit 150 controls the gate of PMOS transistor 120, which is the input to amplifier circuit 152. NMOS transistor 122 forms a current mirror with NMOS transistor 124 with which it has a commonly coupled gate terminals. Resistor R1 and PMOS transistor 126 provide a minimum current to configure NMOS transistor 124, NMOS transistor 122, and PMOS transistor 120 in an operational state when the load current is zero.

PMOS transistor 128 and series-coupled PMOS transistors 132 have commonly coupled gate terminals, thereby forming another current mirror. PMOS transistors 132 are coupled in series between power supply node VDD and the drain terminal of NMOS transistor 124 and have commonly coupled gate terminals. PMOS transistors 132 and 128 may have the same channel length. PMOS transistors 132 and PMOS transistor 128 may have the same effective width. In an embodiment, four PMOS transistors are coupled in series to reduce the effective width to W/4 to obtain a target multiplication factor from PMOS transistors 132 to PMOS transistor 128. The combination of PMOS transistors 132 and PMOS transistor 128 provides a ratio of 1/4:50 (i.e., an effective ratio of 1:200).

The frequency of the second pole of voltage regulator 100 varies with the load current, which may vary during operation of voltage regulator 100. As the dominant pole determined by the load circuit (RL and CL) moves to a higher frequency when load current increases, the second pole moves in frequency in concert with the dominant pole, thereby providing stability and dynamic load regulation

response. Feedback resistor RFB causes the second pole to become a function of the transconductance of PMOS transistor **120**. When the load current increases, the transconductance of PMOS transistor **120** also increases, causing the second pole to move to a higher frequency. Accordingly, sufficient spacing is maintained between the dominant pole and the second pole to realize a target level of phase margin and target dynamic load regulation performance. The dynamic movement of the second pole occurs without increasing internal bias currents, such as the current provided by NMOS transistor **106**, resulting in low power operation of regulator **100** when the load current is low (e.g., in the nanoampere to microampere range).

As reference voltage VREF exceeds the output voltage, the voltage at node **134** decreases. This voltage decrease causes the current flowing through PMOS transistor **120** to increase, thereby increasing the current flowing through PMOS devices **132** and **128**. This increased current flowing through PMOS transistor **128** causes an increase in regulated voltage VREG, thus regulating the output voltage to the reference voltage.

The DC loop gain of voltage regulator **100** is:

$$DC\ loop\ gain = \frac{g_{mn}}{(g_{mpx}R_{fb}g_{mp})} \times N \times g_{mpx} \times R_L = \frac{g_{mn} \times N \times R_L}{R_{fb}g_{mp}},$$

where N is the ratio of the width of NMOS transistor **124** (W_{124}) to the width of NMOS transistor **122** (W_{122}) times the ratio of the width of PMOS transistor **128** (W_{128}) to the width of PMOS transistors **132** (W_{132}) (e.g., $N = (W_{124}/W_{122}) \times (W_{128}/W_{132}) = 2 \times 200 = 400$). As the load current (VREG/RL) increases, the load resistance decreases, which substantially reduces the DC loop gain for high currents. The reduction in DC loop gain for high load currents corresponds to high systematic offset at the output and thus degrades the ability to maintain a constant voltage level on the output node as the load current increases (i.e., degrades load regulation). Accordingly, improved techniques for load regulation are desired.

SUMMARY OF EMBODIMENTS OF THE INVENTION

A voltage regulator includes a first circuit configured to generate a difference signal based on a reference voltage on an input node, a regulated output voltage on an output node, and a signal on a feedback node. The voltage regulator includes a second circuit configured to provide the regulated output voltage on the output node based on the difference signal. The second circuit includes a first transistor coupled to receive the difference signal, a first feedback circuit configured to provide a first feedback signal to the feedback node, and a second feedback circuit and configured to provide a second feedback signal to the feedback node. An open loop frequency response of the voltage regulator may have a first pole at a first frequency and a second pole at a second frequency and the first feedback signal adjusts the second frequency of the second pole based on a load current. The second feedback signal may adjust loop gain based on the load current.

A method for generating a stable output voltage includes generating a regulated voltage based on a difference between a reference voltage on an input node and the regulated voltage according to an open loop frequency response having a first pole at a first frequency and a second pole at

a second frequency. A location of the second pole of the open loop frequency response and a DC loop gain are based on a load current. The DC loop gain of the generating may saturate at high load current. Generating the regulated voltage may include saturating a feedback transconductance with increases to the load current. The first frequency may be several orders of magnitude less than the second frequency.

BRIEF DESCRIPTION OF THE DRAWINGS

The present invention may be better understood, and its numerous objects, features, and advantages made apparent to those skilled in the art by referencing the accompanying drawings.

FIG. 1 illustrates a circuit diagram of a voltage regulator having a feedback circuit.

FIG. 2 illustrates a circuit diagram of a load compensating voltage regulator consistent with at least one embodiment of the invention.

FIG. 3 illustrates a small signal model of the load compensating voltage regulator of FIG. 2.

FIG. 4 illustrates an equivalent small signal model of the load compensating voltage regulator of FIG. 2.

FIG. 5 illustrates transconductance G_{mx} as a function of load current for the voltage regulator circuits of FIGS. 1 and 2.

FIG. 6 illustrates DC loop gain as a function of load current for the voltage regulator circuits of FIGS. 1 and 2.

FIG. 7 illustrates regulated voltage as a function of load current for the voltage regulator circuits of FIGS. 1 and 2.

FIG. 8 illustrates phase margin as a function of load current for the voltage regulator circuits of FIGS. 1 and 2.

FIG. 9 illustrates a circuit diagram of a load compensating voltage regulator having a first feedback circuit and a second feedback circuit for an application having low input common mode voltages consistent with at least one embodiment of the invention.

FIG. 10 illustrates circuit diagram of a load compensating voltage regulator having a first feedback circuit and a second feedback circuit for a low voltage application consistent with at least one embodiment of the invention.

The use of the same reference symbols in different drawings indicates similar or identical items.

DETAILED DESCRIPTION

Referring to FIG. 2, load compensating voltage regulator **200** has stable operation and provides predetermined load regulation across a wide range of load currents. Load compensating voltage regulator **200** compares regulated voltage VREG to reference voltage VREF and adjusts regulated voltage VREG accordingly. This voltage regulation occurs with stable operation, i.e., with a predetermined phase margin and sufficient spacing between a dominant pole and a second pole for load currents that vary over three orders of magnitude.

PMOS transistor **228**, which is coupled between power supply node VDD and output node **230** that couples to a load, provides regulated voltage VREG to the load. This load circuit is represented as a combined resistance and capacitance (RL and CL, respectively). By controlling the output current of PMOS transistor **228**, regulated voltage VREG is regulated to a target level. In an embodiment, PMOS transistor **228** has a source terminal coupled to power supply node VDD, a drain terminal coupled to output node **230**, and a gate terminal commonly coupled with one or

more gate terminals of at least one other PMOS transistor. The gate terminal of PMOS transistor **228** acts as a control terminal to control the current provided to the load by PMOS transistor **228**.

In at least one embodiment of voltage regulator **200**, the control signal provided to the gate terminal of PMOS transistor **228** is generated using two amplifier circuits. Amplifier circuit **150** is a transconductance amplifier including NMOS transistor **102** and NMOS transistor **104**, which are coupled as a differential pair of transistors. Amplifier circuit **150** compares regulated voltage VREG to reference voltage VREF, which in an embodiment is generated by a reference voltage generator (not shown). The source terminals of NMOS transistor **102** and NMOS transistor **104** are coupled to a drain terminal of NMOS transistor **106**, which is configured as a current source that uses bias voltage VBIAS to provide a bias current to the differential pair of transistors.

Drain terminals of NMOS transistor **102** and NMOS transistor **104** provide a differential pair of signals to source terminals of PMOS transistor **112** and PMOS transistor **114**, thereby causing a voltage on node **234** that corresponds to the difference between regulated voltage VREG to reference voltage VREF and is adjusted using a feedback signal on feedback node **236**. NMOS transistor **102** and NMOS transistor **104** have sizes determined to maintain a small random offset of voltage regulator **200**. NMOS transistors **106**, **108**, and **110** have sizes that determine the bias currents in amplifier circuit **150** according to a bias voltage VBIAS, which is generated by a bias voltage generator (not shown).

PMOS transistors **116** and PMOS transistor **118** have commonly coupled gate terminals and typically have the same size. The source terminal of PMOS transistor **118** is coupled to power supply node VDD and a drain terminal of PMOS transistor **118** is coupled to the drain terminal of NMOS transistor **102**. However, PMOS transistor **116** is coupled between a drain terminal of PMOS transistor **104** and feedback node **236** to receive a feedback signal generated using feedback resistor RFB1 and feedback transconductance G_{mx}. PMOS transistor **116** and PMOS transistor **118** are asymmetrically coupled (e.g., do not have commonly coupled source terminals) which improves stability. A second feedback path including NMOS transistor **208** and feedback resistor RFB2 is coupled to feedback node **236**.

The input to the second amplifier circuit is received by the gate terminal of PMOS transistor **212**, which has a source terminal coupled to power supply node VDD. PMOS transistor **212** has a size selected to control the stability and the DC loop gain of voltage regulator **200**. The drain terminal of PMOS transistor **212** is coupled to a current mirror formed by NMOS transistor **210** and NMOS transistor **224**. In an embodiment of the current mirror, NMOS transistor **210** and NMOS transistor **224** have the same size, which is selected to maintain these transistors in the saturation region of operation.

PMOS transistors **232** use the mirrored current to generate a control voltage provided to PMOS transistor **228** to control the load current provided to output node **230**. In an embodiment of voltage regulator **200**, resistor R1 and PMOS transistor **226** provide a minimum current to configure NMOS transistor **224**, NMOS transistor **208**, NMOS transistor **210** and PMOS transistor **212** operational when the load current is zero (e.g., a substantially high load resistance RL), instead of being off when the load current is zero. PMOS transistor **226** and PMOS transistors **232**. PMOS transistor **228** is several times larger than PMOS transistors **232** thereby providing output current multiplication for the

generating the load current. In an embodiment, four PMOS transistors are coupled in series to reduce the effective width to W/4 to obtain a target multiplication factor from PMOS transistors **232** to PMOS transistor **228**. In an embodiment, only one PMOS transistor is used instead of PMOS transistors **232** and PMOS transistor **228** is four times larger. The combination of PMOS transistors **232** and PMOS transistor **228** provides a ratio of 1/4:50 (i.e., an effective ratio of 1:200). Reducing the size of PMOS transistor **228** reduces its current driving capability which limits further reduction in the size of PMOS transistor **228** for some applications.

In addition to a feedback path provided by coupling RFB1 to feedback node **236**, an additional feedback path couples feedback transconductance G_{mx} to feedback node **236**. In an embodiment, feedback transconductance G_{mx}, which is coupled to ground, includes NMOS transistor **208** and feedback resistor RFB2 and controls the voltage on feedback node **236**. The voltage on feedback node **236** dynamically controls operation of error amplifier circuit **150** based on the load current. Feedback resistor RFB1 and feedback resistor RFB2 dynamically adjusts a location of the second pole of voltage regulator **200** based on the load current.

Referring to FIGS. 2, 3, and 4, small signal diagram **300** and simplified small signal model **400** are used to derive the following equations for first pole ω_{p1} , second pole ω_{p2} , and DC loop gain for voltage regulator **200**. Similar to voltage regulator **100** described above, the load circuit of voltage regulator **200** provides dominant pole ω_{p1} for voltage regulator **200**:

$$\omega_{p1} = \frac{1}{R_L C_L}.$$

In an exemplary embodiment of voltage regulator **200**, the feedback transconductance is:

$$G_{mx} = \frac{g_{mpx}}{g_{mdio}} \cdot \frac{g_{mnx}}{1 + RFB2 g_{mnx}}$$

Feedback transconductance G_{mx} increases with increasing load current, but saturates at higher load currents. As a result, the DC loop gain and the second pole are dynamically adjusted based on the load current:

$$DC\ Gain = \frac{g_{mn}}{g_{dsn} + g_{mp} G_{mx} RFB1} \times \frac{Ng_{mpx}}{R_L};$$

and

$$\omega_{p2} = \frac{g_{dsn} + g_{mp} G_{mx} RFB1}{C_1},$$

where N is a predetermined design parameter (e.g., **400**) that provides independent control over the DC loop gain and current multiplication for the load current is predetermined according to the target application. For example, N is the ratio of the width of NMOS transistor **224** (W₂₂₄) to the width of NMOS transistor **210** (W₂₁₀) times the ratio of the width of PMOS transistor **228** (W₂₂₈) to the width of PMOS transistors **232** (W₂₃₂) (e.g., N=(W₂₂₄/W₂₁₀)×(W₂₂₈/W₂₃₂) =2×200=400). In other embodiments of voltage regulator **200**, other ratios are used. When the load current increases, feedback transconductance G_{mx} **504** increases but saturates at higher load currents.

That is, as the load current increases, G_{mX} does not match the increase in high load current with a linear relationship and asymptotically approaches transconductance **506**, which is $1/R_{FB2}$. However, transconductance G_{mX} **502** for voltage regulator **100** described above (which does not include R_{FB2}) does not saturate and continues to increase linearly with increased load current. As reference voltage V_{REF} increasingly exceeds output voltage V_{REG} , the voltage at node **234** decreases, which causes the current flowing through PMOS transistor **212** to increase, thereby increasing the current flowing through PMOS devices **232** and **228**. This increase causes an increase in regulated voltage V_{REG} , thus regulating the output voltage to the reference voltage. Note that R_{FB2} can be coupled in other locations of a loop formed by PMOS transistor g_{mPx} , NMOS transistor g_{mDio} , R_{FB2} , and NMOS transistor g_{mNx} of voltage regulator **200**, voltage regulator **900**, or voltage regulator **1000**.

Referring to FIGS. 1, 2, and 6, in at least one embodiment, R_{FB2} is at least one order of magnitude greater than R_{FB1} . DC loop gain **604** of voltage regulator **100** decreases from approximately 90 dB to approximately 21 dB with increases to load current of over three orders of magnitude. In comparison, DC loop gain **602** of voltage regulator **200** decreases from approximately 90 dB to approximately 48 dB over the same range of load current, which is an acceptable amount of DC loop gain for a target application.

Referring to FIGS. 1, 2, and 7, unlike voltage regulation **702** of voltage regulator **100**, which is substantially constant only at low currents (e.g., load currents of up to 10 micro-ampères (μ A)), voltage regulation **704** of voltage regulator **200** is substantially constant for load currents across several orders of magnitude, e.g., currents from μ A through milli-ampères (mA). Referring to FIGS. 1, 2, and 8, phase margin **802** of voltage regulator **100** varies substantially with load current variation and varies from approximately 60 degrees to approximately 90 degrees with increases to the load current. Phase margin **804** of voltage regulator **200** has less variation with increases to load current and remains between 55 and 70 degrees of phase margin, which is an acceptable range of phase margin performance for a target application.

Referring to FIGS. 2, 9, and 10, a second feedback path including a feedback transconductance may be implemented in other voltage regulator topologies to maintain stability and DC performance for a voltage regulator used in different applications. For example, voltage regulator **200** includes a folded cascode stage that is suited for target applications having higher input common mode voltages (e.g., common mode voltages in the range of 0.7V-0.9V for V_{DD} as low as 1.5V). The folding about the cascode node increases the input and output voltage swing range as compared to a voltage regulator without a folded cascode stage. However, a voltage regulator using a reduced number of transistors may be used in target applications having lower input common mode voltages (e.g., input common mode voltages in a range that just maintain NMOS transistor **102** and NMOS transistor **104** in the saturation mode of operation) by excluding a folded cascode stage. For example, voltage regulator **900** does not include a folded cascode stage, has fewer transistors, and consumes less power than voltage regulator **200**. Furthermore, voltage regulator **1000** implements only one amplifier for a target application that requires less gain, thereby reducing power consumption as compared to a voltage regulator including two amplifier stages. A signal indicative of the difference between reference voltage V_{REF} and regulated voltage V_{REG} directly controls a transistor that delivers current to the load.

Thus, voltage regulator topologies that have sufficient stability to reduce or eliminate oscillation in operation (i.e., very low transient overshoot and undershoot voltages, e.g., transient overshoot and undershoot voltages of less than 1% of output voltage) and sufficient load regulation across a wide range of load currents (i.e., load currents that may vary by multiple orders of magnitude) have been described. For example, as the load current varies from 1 μ A to 3 mA, regulated voltage V_{REG} drops by 4 mV and for regulated voltage V_{REG} of 0.9 V, the load regulation is approximately 0.44%. The voltage regulators maintain sufficient DC loop gain and a separation over multiple orders of magnitude in frequency of the first and second poles in the open loop frequency response.

The description of the invention set forth herein is illustrative and is not intended to limit the scope of the invention as set forth in the following claims. For example, while the invention has been described in an embodiment in which the input differential pair of transistors are NMOS, one of skill in the art will appreciate that the teachings herein can be utilized with complementary transistor embodiments, e.g., embodiments of a voltage regulator using PMOS transistors as the input differential pair of transistors in a voltage regulator having a topology consistent with voltage regulators **200**, **900**, and **1000** of FIGS. 2, 9, and 10. The terms "first," "second," "third," and so forth, as used in the claims, unless otherwise clear by context, is to distinguish between different items in the claims and does not otherwise indicate or imply any order in time, location or quality. For example, "a first received signal," "a second received signal," does not indicate or imply that the first received signal occurs in time before the second received signal. Variations and modifications of the embodiments disclosed herein may be made based on the description set forth herein, without departing from the scope of the invention as set forth in the following claims.

What is claimed is:

1. A voltage regulator comprising:
a first circuit configured to generate a difference signal based on a reference voltage on an input node, a regulated output voltage on an output node, and a signal on a feedback node; and
a second circuit configured to provide the regulated output voltage on the output node based on the difference signal, the second circuit comprising:
a first transistor coupled to receive the difference signal;
a first feedback circuit configured to provide a first feedback signal to the feedback node; and
a second feedback circuit coupled to the first transistor and configured to provide a second feedback signal to the feedback node,
wherein an open loop frequency response of the voltage regulator has a first pole at a first frequency and a second pole at a second frequency and the first feedback signal adjusts the second frequency of the second pole based on a load current, and
wherein the second feedback signal adjusts loop gain based on the load current.
2. The voltage regulator as recited in claim 1, wherein the first frequency is several orders of magnitude less than the second frequency.
3. The voltage regulator as recited in claim 1, wherein the second circuit further comprises:
an amplifier circuit configured to generate a control signal based on the difference signal.

4. The voltage regulator as recited in claim 3, wherein the first transistor is coupled between a first power supply node and the output node.

5. The voltage regulator as recited in claim 1, wherein the first feedback circuit comprises a first resistance coupled between the feedback node and a first power supply node; and wherein the second feedback circuit comprises a feedback transconductance coupled between the feedback node and a second power supply node.

6. The voltage regulator as recited in claim 5, wherein the feedback transconductance comprises:

a p-type transistor coupled to the second power supply node and controlled by the difference signal; and a second resistance coupled between the feedback node and a source of the p-type transistor.

7. The voltage regulator as recited in claim 6, wherein the second feedback circuit further comprises:

an n-type transistor coupled between the feedback node and the second resistance.

8. The voltage regulator as recited in claim 6 wherein the second resistance is at least one order of magnitude greater than the first resistance.

9. The voltage regulator as recited in claim 5 wherein the feedback transconductance saturates at high load currents.

10. A method for generating a stable output voltage, the method comprising:

generating a regulated voltage based on a feedback signal and a difference between a reference voltage and the regulated voltage and according to an open loop frequency response having a first pole at a first frequency and a second pole at a second frequency, wherein a location of the second pole of the open loop frequency response and a DC loop gain of the generating are based on a load current.

11. The method as recited in claim 10 wherein generating the regulated voltage comprises saturating a feedback transconductance with increases to the load current.

12. The method as recited in claim 10 wherein the first frequency is several orders of magnitude less than the second frequency.

13. The method as recited in claim 10 wherein generating the regulated voltage comprises:

generating a difference signal based on the reference voltage and the regulated voltage.

14. The method as recited in claim 10 wherein generating the regulated voltage comprises:

generating the regulated voltage based on the difference; sourcing a first current into a feedback node using a first resistance; and sinking a second current from the feedback node using a second resistance.

15. The method as recited in claim 14 wherein the second resistance is at least one order of magnitude greater than the first resistance.

16. The method as recited in claim 10 wherein generating the regulated voltage further comprises:

amplifying the difference to generate a control signal; and wherein the regulated voltage is generated using the control signal.

17. An apparatus comprising:

means for generating a regulated voltage based on a difference between a reference voltage and the regulated voltage according to an open loop frequency response having a first pole at a first frequency and a second pole at a second frequency;

means for adjusting the second frequency of the second pole based on a load current; and

means for compensating for a reduction in DC loop gain caused by adjusting the second frequency of the second pole.

18. The voltage regulator as recited in claim 5 wherein the feedback transconductance saturates with increases to the load current.

19. The voltage regulator as recited in claim 5 wherein the first resistance and the feedback transconductance are directly coupled to the feedback node.
